Assistant Examiner — Michael A Maharajh(74) *Attorney, Agent, or Firm* — Wyatt, Tarrant & Combs, LLP; Max E. Bridges; Matthew A. Williams(57) **CLAIM**

The ornamental design for a vibration machine, as shown and described.

DESCRIPTION

FIG. 1 is a top perspective view of the vibration machine, showing my new design;

FIG. 2 is a bottom perspective view thereof;

FIG. 3 is a top plan view thereof;

FIG. 4 is a bottom plan view thereof;

FIG. 5 is a rear view thereof;

FIG. 6 is a front view thereof;

FIG. 7 is a left-side view thereof; and,

FIG. 8 is a right-side view thereof.

The broken lines shown in the drawings are for the purposes of illustrating portions of the vibration machine, which form no part of the claimed design.

1 Claim, 8 Drawing Sheets(56)
